UNITED STATES PATENT OFFICE.

CHARLES W. HOTTMANN, OF PHILADELPHIA, PENNSYLVANIA, ASSIGNOR OF ONE-HALF TO AUGUST H. E. JUERGENS, OF PHILADELPHIA, PENNSYLVANIA.

CHOPPING AND MIXING MACHINE.

1,111,694.

Specification of Letters Patent. Patented Sept. 22, 1914.

Application filed July 6, 1914. Serial No. 849,208.

To all whom it may concern:

Be it known that I, CHARLES W. HOTTMANN, a citizen of the United States, residing in the city and county of Philadelphia, State of Pennsylvania, have invented a new and useful Chopping and Mixing Machine, of which the following is a specification.

My present invention consists of a novel chopping and mixing machine, which is constructed in such a manner that the device which operates on the articles or material within the machine may be readily removed, thereby enabling the operator to have free access to the material which has been chopped or mixed, and also enabling one to maintain the parts of the machine in a sanitary condition at all times.

It further consists of a novel machine of the character stated, wherein novel means are employed for mounting the container which is to receive the material to be treated, and novel means for imparting a continuous rotation to said container.

It further consists of a novel manner of actuating the cutting or chopping blade, whereby a sliding or draw cut is produced.

It further consists of a novel construction of a frame-work for supporting the container, and novel means for imparting to the cutting or chopping blade or other device employed, a lateral travel, during the raising and lowering thereof.

Other novel features of advantage and construction will more clearly hereinafter appear in the detailed description.

For the purpose of illustrating my invention, I have shown in the accompanying drawings, one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities, as herein shown and described.

Figure 1 represents a side elevation of a chopping and mixing machine, embodying my invention. Fig. 2 represents a section on line α — α of Fig. 1. Fig. 3 represents a top plan view of my machine, certain parts thereof having been removed for the sake of clearness of illustration. Fig. 4 represents a top plan view of a bearing member in de-

tached position. Fig. 5 represents a sectional elevation of a portion of my machine.

Similar numerals of reference indicate corresponding parts in the figures.

Referring to the drawings:—1 designates the frame-work of a chopping and mixing machine, embodying my invention, and the construction of said frame-work may vary widely in practice. In the form shown herein, the frame-work 1 has removably connected therewith, by means of fastening devices 2, a bracket 3, in which is journaled the main driving shaft 4, the latter being also journaled in a bracket 5.

6 designates the main driving gear, which is provided with a grasping handle 7, whereby the shaft 4 may be manually actuated, it being understood that it is also within the scope of my invention to mechanically drive the shaft 4 by any desired mechanism, but since such mechanism is old in the art, I have deemed it unnecessary, in the present instance, to illustrate and describe the same. The brackets 3 and 5 are connected with a spider 8, which forms a bearing member and is provided with the bearing lugs 9, and a centrally located aperture 10, it being seen that the lugs 9 are located in proximity to the arms of the spider in order to give the maximum strength and rigidity to the machine. In the present instance, I have shown the bracket 5 secured to the spider 8. The bracket 3 is secured to such spider in any desired manner.

11 designates a support, consisting, in the present instance, of a spider, which is adapted to receive a fastening device 12, which maintains the support 11 in assembled condition with respect to the spider 8, said fastening device, in the present instance, consisting of a screw, provided with a plurality of nuts, one of which serves as a lock nut. The support 11 is provided with a downwardly depending annular flange 13, the lower face of which is provided with teeth 14, thereby forming a gear, which is adapted to mesh with a pinion 15 mounted on the driving shaft 4, it being seen that the side wall of the spider 8 is within the flange 13, when the parts are in assembled condition. The support 11 is provided with a desired number of upwardly extending lugs 16, two of the same being shown for purposes of illustration, and I have also shown a spring 17, so that the same will interlock 110

with the external bead or rib 18 of a container 19 for the material to be treated. By such construction, the container 19 is retained in proper position on the support 11, during the operation of the machine, and it can be readily removed, when desired. The spider 8, in the present instance, has integral therewith, a bracket 20, a portion of which is secured to the frame-work 10 1 by means of a fastening device 21, and said bracket is provided with a portion extending upwardly above the bottom of the container 19, and at its upper end, it forms a bearing 22. The gear 6 meshes with a 15 pinion 23 mounted on a shaft 24, journaled in the machine frame, said shaft having also mounted thereon, a disk 25, having a crank-pin 26 eccentrically located thereon.

27 designates a crank-arm or connection-20 rod, one end of which is mounted on the pin 26 and secured with respect thereto, by means of a fastening device 28. The outer or free end of said crank-arm 27 is in sliding engagement with a guide 29, which latter is provided with an aperture 30 there-through, through which the crank-arm 27 extends. The guide 29 is provided with a reduced neck 31, which is journaled in the bearing 22 and maintained in assembled 25 position with respect thereto, by means of a pin 32, passing through the reduced neck 31. The upper end of the crank-arm 27 has the screws or threaded pin 33 passing there-through and provided with thumb-nuts 34, 30 whereby the cutter arm 35 may be secured with respect to the crank-arm 27, it being seen that said cutter arm 35 is provided with slots 36, extending through the side wall thereof. The arm 35 is deflected laterally 35 and downwardly at an angle to the crank-arm 27 and has secured to its lower end, a cutting or chopping blade or tool 37, in any desired manner, it being understood that the blade 37 may have substituted therefor, any 40 desired type of mixing or stirring member. The blade 37 is provided on its bottom face with a preferably curved cutting face, as at 38, which merges into the upwardly curved cutting face 39, which extends through the 45 forward end thereof. If desired, a wooden or other block 40 may be placed in the bottom of the container 19, in order to prevent injury to the container 19.

The operation of my novel chopping and 50 mixing machine will now be apparent to those skilled in the art to which my invention appertains, and is as follows:—Assuming that the machine is to be manually operated, and that the material to be treated has 55 been placed in the container 19, the operator, by means of the handle 7, causes the shaft 4 to be rotated, and since the pinion 15 is in mesh with the gear 14, the container will continuously revolve. Since the gear 6 is 60 in mesh with the pinion 23, the disk 25 will

be rotated, thereby causing the crank-arm 27 to be reciprocated in the guide 29, and owing to the provision of said guide, the blade 37 will not only be raised and lowered, but will have an oscillatory movement 70 imparted thereto, so that a sliding or draw cut on the material within the container is produced. This movement also causes a radial movement of the material within the container 19, with respect to the axis of said 75 container. It will be seen that the crank-arm 27 is curved at its lower end, thereby enabling me to locate the driving means for said crank-arm substantially beneath the container, so that the machine will take up 80 but a minimum amount of space. When it is desired to move the material which has been cut or mixed, depending upon the character of blade or implement, which has been employed, the arm 35, as is apparent, 85 will not interfere with the removal of such material, and, if desired, such arm can be readily removed by actuating the thumb nuts 34, as is apparent. Special attention is directed to the fact that the container is 90 continuously rotated, and that the cutter arm travels in close proximity to one side of the container, so that the necessary space is left for the proper inspection and handling of the material treated. Attention is 95 directed to the novel manner of constructing, supporting and actuating the support for the container, as well as novel means employed for actuating any cutting, chopping or other blade employed.

100 It will now be apparent that I have devised a novel and useful chopping and mixing machine, which embodies the features of advantage enumerated as desirable in the statement of the invention and the above 105 description, and while I have, in the present instance, shown and described a preferred embodiment thereof, which will give in practice, satisfactory and reliable results, it is to be understood that the same is susceptible of modification in various particulars without departing from the spirit or scope 110 of the invention or sacrificing any of its advantages.

Having thus described my invention, 115 what I claim as new and desire to secure by Letters Patent, is:—

1. A device of the character stated, comprising a container, means to continuously rotate said container, a crank arm, a tool 120 operatively connected with said crank arm and extending within said container, a pivotally mounted guide for said crank arm, and actuating means for said crank arm.

125 2. A device of the character stated, comprising a spider having bearing members thereon, a support mounted on said spider and provided with a gear, a container carried by said support, a crank disk, a crank 130

arm connected with said disk, a pivotally mounted guide through which the upper end of said arm passes, a tool located within the container and removably connected to the crank arm, and means to revolve said support and said crank disk.

3. A device of the character stated, comprising a spider having bearing members thereon and provided with a bracket, a support mounted on said spider and provided with a gear, a container carried by said support, a crank disk, a crank arm connected with said disk, a guide pivotally mounted in said bracket through which the upper end of said crank arm passes, a tool located within the container and removably connected to the crank arm, and means to revolve said support and said crank disk.

4. A device of the character stated, comprising a framework, a spider carried thereby, a support rotatably mounted on said spider, means to maintain said support and spider in assembled position, a container mounted on said support, a gear carried by

said support, a driving shaft operatively connected with said gear, a cam disk operatively connected with said driving shaft, a bracket, an apertured guide movably carried by said bracket, a crank arm passing through the aperture of said guide, a cutter arm having one end secured to said crank arm and its other end extending into said container, and a working tool carried by said cutter arm.

5. A device of the character stated, comprising a container, means to revolve the same, a working tool within the container, a connection from said working tool, means to vertically reciprocate said connection, and a guide with which said connection is in sliding engagement, said guide being pivotally supported in a horizontal plane lying above the bottom of said container.
